UNITED STATES PATENT OFFICE

WILFRED SHURTLEFF, OF MOLINE, ILLINOIS, ASSIGNOR TO THE HERMAN NELSON CORPORATION, OF MOLINE, ILLINOIS, A CORPORATION OF ILLINOIS

HEATING AND VENTILATING UNIT

Application filed November 17, 1930. Serial No. 496,362.

In heating and ventilating units of the type to which the present invention relates, it is desirable to so arrange the structure that it will discharge a stream of air upwardly at 5 high velocity and in position to impinge against the ceiling of the room and thereafter be distributed and disseminated to all portions of the room.

In order to provide for the effective operation of such device, it is desirable to so arrange the air inlets and passages as to minimize unnecessary turning or deflection of the air currents in their passage through the unit in order to operate the fan or blower most 15 efficiently in providing for the discharge of high velocity currents of air.

The unit of the present invention conforms to the above requirements and at the same time makes provision for the admission 20 either of indoor air for purposes of recirculation, or outdoor air to secure a proper cooling effect when required, and also makes provision to prevent back drafts from the outdoor inlet under heavy wind pressure 25 from finding entrance into the room through the indoor air recirculation inlet.

The invention is also designed to simplify the structure as much as possible and to so locate the various features comprising the 30 unit as a whole, that it will subserve its intended function in the most satisfactory and efficient manner.

Further objects and details of the invention will appear from the description thereof 35 in conjunction with the accompanying drawing, wherein Fig. 1 is a vertical cross-sectional elevation through the cabinet and Fig. 2 a vertical elevation with the front wall removed to illustrate interior arrangement.

The unit as a whole comprises a cabinet 40 having front wall 10, rear wall 11, end walls 12-12, a flat top 13 and a base 14.

The interior of the cabinet is divided by means of a horizontal partition wall 15 and a 45 vertical partition wall 16 to provide a radiator chamber 17, a hot air chamber 18, a cold air chamber 19 and a fan chamber 20.

The radiator chamber occupies the space at the base of the cabinet immediately 50 beneath the horizontal partition wall 15 and the

front wall of the cabinet adjacent this space is apertured to provide an indoor air inlet 21 which extends from end to end of the radiator at a point close to the floor level.

Within the radiator chamber is located a light-weight radiator 22 of high radiating 55 capacity, which extends from end to end of the cabinet immediately behind the recirculation air inlet. The radiator in the form here shown comprises a wedge-shaped core 23 upon which are threaded a multiplicity of closely spaced plates or fins 24. The core and fins are preferably formed of metal having high thermal conductivity, and the plates or fins are closely wedged on to the core of the radiator to afford a close metal to metal contact for the purpose of promoting thermal 60 conductivity.

The hot air chamber 18 occupies the space 65 immediately behind the radiator chamber and immediately beneath the cold air chamber 19 and between the chambers 18 and 19 is located a damper 25 which when closed spans the space between the rear wall and the rear edge of the horizontal partition wall 15 and when thus adjusted, serves to block 70 off the circulation of air through the radiator.

The rear wall 11 of the cabinet is provided 75 in its center with an outdoor air inlet aperture 26, which is surrounded by an exteriorly 80 projecting flange 27 furnishing an outdoor air conduit through the rear wall of the cabinet and within this conduit is located a damper comprising, as shown, a plurality 85 of adjustable leaves or sections 28 which, when standing vertically, will close the inlet, and when standing horizontally, will open the inlet to its fullest extent.

Within the fan chamber is located a fan 90 29 having its inlet 30 projecting through the partition wall 16 and into the cold air chamber 19. The fan is driven by a motor 31 and the fan and motor rest upon and are supported by the partition wall 15.

As shown, the fan is surrounded by an 95 arch-shaped filter 32, the base of which rests upon the partition wall 15 and the upper portion of which arches over the fan so that air discharged from the periphery of the fan 100

will be driven through the filter and ultimately delivered at high velocity through the air discharge opening in the top of the cabinet, which in the form shown, is afforded by a grill 32 having bars or divisions 33 which are preferably of tapered or stream-like formation and tilted slightly forward to discharge the air current upwardly at high velocity and with a slight inclination toward the interior of the room. Suitable means are provided for adjusting the hot air and cold air dampers either manually or by thermostatic control, but these features form no portion of the present invention and need not be described in detail.

Operation

In the operation of the unit, it is the customary practice when the room temperature is objectionably low, to shut the outdoor air damper and open the hot air damper to the fullest extent and recirculate the indoor air until the latter has been heated to the desired temperature, at which time the supply of steam or other heating medium to the radiator will be shut off and indoor air recirculated, without being additionally heated, the discharge of the recirculated air at high velocity serving to maintain the air throughout the room in a gentle motion which is conducive to the comfort of the occupants.

If the room temperature should rise above a comfortable degree, the outdoor inlet damper may be opened, either partially or wholly, and the hot air damper closed either wholly or partially, which serves to admit fresh outdoor air in the volume required to maintain comfortable conditions within the room. Where heavy wind pressure might tend to cause back drafts through the recirculation air inlet, it is desirable to fully close the hot air damper against the admission of such back draft before the cold air damper is completely opened, so as not to permit the fan to be over-loaded under wind pressure beyond its normal capacity.

However, the arrangement of the structure is one which guards against such abnormal operation, since the outdoor air inlet is located directly opposite the mouth of the fan so that the entire volume of outdoor air will normally find its way immediately into the fan and only rarely will tend to find egress downwardly and through the recirculation air inlet. At the same time the location of the radiator, immediately adjacent the recirculation air inlet, is such as to cause an immediate heating of air as soon as it is sucked into the unit and the normal travel of either hot air or cold air through the device is in a relatively direct line without serious deflection and without being forced through sinuous or restricted passageways so that the fan may be operated at moderate speed to produce an adequately high velocity of dis-

charge to subserve the purposes of the present invention.

The construction and arrangement of the parts is simple in the extreme and free from complications which might tend to increase the cost or decrease the efficiency of the apparatus. Although the invention has been described with considerable particularity as to detail, it is not the intention unless otherwise indicated in the claims, to limit the invention to the specific details shown, since departures therefrom are within the scope of the invention.

I claim:

1. In a unit heating and ventilating device, the combination of a cabinet provided near its base with an indoor air inlet, a radiator located near the base of the cabinet and in alignment with the indoor air inlet, the cabinet being also provided in its rear wall with an external air inlet, and a fan located above the radiator and having its intake in alignment with the external air inlet and the cabinet being provided with a discharge outlet above the fan.

2. In a unit heating and ventilating device, the combination of a cabinet provided near its base with an indoor air inlet, a radiator located near the base of the cabinet and in alignment with the indoor air inlet, the cabinet being also provided in its rear wall with an external air inlet, and a fan located above the radiator and having its intake in alignment with the external air inlet and the cabinet being provided with a discharge outlet above the fan; a damper interposed between the radiator and the fan for controlling the flow of air admitted through the indoor air outlet, and the external air inlet being provided with a damper for controlling the flow of air therethrough.

3. In a heating and ventilating unit, the combination of a cabinet provided with a horizontally extending partition wall and a vertically extending partition wall serving to divide the cabinet into a radiator chamber in the base of the cabinet, a hot air chamber behind the radiator chamber, a cold air chamber above the hot air chamber and behind the vertical partition wall, and a fan chamber in front of the vertical partition wall and above the horizontal partition wall, the cabinet being provided in its front wall near the base with a horizontally elongated aperture constituting an indoor air inlet opening directly into the radiator chamber, being provided in its rear wall with an external air inlet opening directly into the cold air chamber and being provided in its top with an air discharge outlet, a radiator located within the radiator chamber and immediately behind the indoor air inlet, a fan located in the fan chamber and having its mouth entered into the cold air chamber in immediate proximity to the external air inlet, and dampers for con-

trolling the flow of air to the fan from the radiator chamber and from the external air inlet, respectively, and the discharge thereof from the fan chamber through the air discharge outlet; and an air filter located within the fan chamber and configured to overhang the upper portion of the fan in position to provide for filtering of the air discharged from the fan and prior to its discharge from the discharge outlet.

4. In a heating and ventilating unit, the combination of a cabinet or a box-like formation comprising a front wall, a rear wall, end walls and a top and having on its interior a horizontal partition wall connected at its rear edge with a vertical partition wall dividing the interior of the cabinet into a radiator chamber underlying the horizontal partition wall, a cold air chamber between the vertical partition wall and the rear wall of the cabinet, a hot air chamber located below the cold air chamber and behind the radiator chamber and a fan chamber located above the horizontal partition wall and in front of the vertical partition wall, the top of the cabinet being provided with an elongated discharge opening, the front wall of the cabinet being provided with a horizontally elongated indoor air inlet opening into the radiator chamber, and the rear wall being provided at a higher elevation with an exterior air inlet opening into the cold air chamber; a horizontally elongated radiator extending from end to end of the cabinet and located within the radiator chamber, a fan located within the fan chamber and having its mouth opening into the cold air chamber in alignment with the external air inlet, a hot air damper interposed between the hot air chamber and the cold air chamber, and a cold air damper for regulating the inflow of air through the external air inlet.

5. In a heating and ventilating unit, the combination of a cabinet comprising front and rear walls, end walls and a top and having on its interior a horizontal partition wall and a vertical partition wall dividing the cabinet into a radiator chamber near the base of the cabinet and below the horizontal partition wall, a hot air chamber in the base of the cabinet and to the rear of the radiator chamber and a cold air chamber behind the vertical partition wall and above the hot air chamber, the front wall of the cabinet being provided near its base with an elongated indoor air inlet opening into the radiator chamber, the rear wall being provided with an external air inlet opening into the cold air chamber and the top of the cabinet being provided with a discharge opening; a light-weight radiator composed of metal having high radiating capacity and an extended radiating surface and located within the radiator chamber, a fan located within the fan chamber and having its mouth entered into the cold air

chamber, a hot air damper interposed between the hot air chamber and the cold air chamber, and a cold air damper located in the external air inlet.

6. In a unit heating and ventilating device, the combination of a cabinet provided in its front wall near its base with an indoor air inlet, a radiator located near the base of the cabinet and immediately behind the indoor air inlet, the cabinet being also provided in its rear wall with an external air inlet, and a fan located above the radiator and immediately in front of the external air inlet, and having its intake in communication with the external and internal air inlets, and the cabinet being provided with a discharge outlet above the fan, and means for controlling the flow of air from the indoor air inlet and from the external air inlet respectively.

In witness that I claim the foregoing I have hereunto subscribed my name this fourth day of November, 1930.

WILFRED SHURTLEFF.
